UNITED STATES PATENT OFFICE.

FRED S. PAYNE, OF BOSTON, MASSACHUSETTS.

SAFETY DEVICE FOR ELEVATORS.

No. 809,320.

Specification of Letters Patent.

Patented Jan. 9, 1906.

Application filed April 20, 1905. Serial No. 256,618.

To all whom it may concern:

Be it known that I, FRED S. PAYNE, a citizen of the United States, residing at Boston, in the county of Suffolk and State of Massachusetts, have invented new and useful Improvements 5 in Safety Devices for Elevators, of which the following is a specification, reference being had to the accompanying drawings.

My present invention relates to that class 10 of safety devices for elevators in which the device is designed to prevent the fall of the elevator-car, which would otherwise result from the breaking or pulling out of the lifting-cables whenever the car fails to stop at the proper limit of its upward travel.

The objects of my invention are to provide 15 a safety device which shall instantly catch and hold the elevator-car should the hoisting machinery either through the negligence of the operator or any defect in the machinery fail to stop when the car has reached the proper limit of its upward travel and the car be thus allowed to pass the point of safety. I accomplish these objects by the means hereinafter specified and as illustrated in the accompanying drawings.

Figure 1 represents a side elevation of a portion of an elevator-shaft, the top part of an elevator-car with its lifting-cables; the 20 overhead beams, sheaves, &c., and my invention as herein described. Fig. 2 is an enlarged detail of the front elevation of my invention with dotted lines showing device when locked, some of the parts being shown 25 partially in section. Fig. 3 is a side elevation of tongue-piece H.

A represents the elevator-car; B, the cross-head to which are attached lifting-cables E; C, the overhead beams supporting sheaves D D; 30 E, the lifting-cables attached to cross-head B and passing over sheaves D D to the winding-drum (not shown) of the operating mechanism.

F F represent the ordinary guide-shoes attached to cross-head B and in engagement 45 with guide-rails G G.

H H are tongue-pieces rigidly attached to overhead beams C and having shank h and movable latches h' h'. Latches h' h' are attached to shank h by means of studs h² h² and 50 are normally kept open or apart by means of springs h³ h³ in addition to the force of gravitation.

I preferably construct shank h with a recess, as at h⁴, so as to allow latches h' h' to 55 fold up when passing through aperture h⁵ of

plate h⁶ and also so as to form a solid bearing-surface for the lower ends of latches h' h'. Plate h⁶ is rigidly attached to the elevator-car, preferably to cross-head B.

In the construction herein shown I have 60 adopted for the purpose of clearly illustrating the position of the various parts I-beams h⁷ and show plate h⁶ as being attached thereto and the beams h⁷ as being attached to cross-head B. In order to prevent the possible 65 shearing-off of latches h' h', I preferably provide shoulders h⁸ h⁸ on plate h⁶, which allow latches h' h' to open only to a given point sufficiently to give bearing-surface to the top of latches h' h' when interlocked with plate h⁶. 70

While Fig. 1 of the drawings accompanying the foregoing specification shows my invention in duplicate as applied to an elevator, I do not limit myself to such construction. For instance, I may change the location of 75 the device and have but one tongue-piece and one plate, or I may have one tongue-piece and one latch thereon or two tongue-pieces with one latch each, in either of which cases my invention would still be operative. 80

My invention operates as follows: Whenever the elevator-car is allowed to ascend sufficiently, plate h⁶ will commence to pass upward on tongue-piece H, the aperture h⁵ being of sufficient size to allow a clear passage. 85 As the upward movement of the car continues, latches h' h' will be forced back toward each other on shank h against the action of springs h³ h³ until plate h⁶ shall have passed upward and beyond the upper end of latches h' h'. 90 The action of springs h³ h³ and the force of gravitation will then immediately cause latches h' h' to open outward and downward until they come into contact with shoulders h⁷ h⁷, thus interlocking plate h⁶ and tongue-piece 95 H. In the event of the breaking, pulling out, or slackening of cables E the elevator-car will thus be suspended from overhead beams C. The weight of the car will prevent the slipping or even the forcible pulling back 100 of latches h' h' until said car has been lifted in some manner and the pressure upon latches h' h' relieved.

What I claim, and desire to secure by Letters Patent, is—

1. A safety device comprising a tongue-piece, a latch normally open, movably attached thereto, and a plate having an aperture, said tongue-piece and said plate being attached, one to the elevator-car, the other to some sup- 110

- port outside the car and both said tongue-piece and said plate being so arranged as to interlock whenever the elevator-car ascends beyond a given point within the elevator-shaft.
5. 2. A safety device comprising a tongue-piece having a shank with latches normally open, movably attached to said shank, said tongue-piece being rigidly attached to some support above the elevator-car and a plate 10 having an aperture, said plate being rigidly attached to the elevator-car; said tongue-piece and said plate being so arranged as to interlock whenever the elevator-car passes a given point.
15. 3. A safety device for elevators consisting of the combination of two interlocking members, one member being a tongue-piece with latches normally open, movably attached within a recess to said tongue-piece, the other member being a plate with an aperture adapted to allow the passage of said tongue-piece through said plate.
20. 4. A safety device consisting in the combination of a tongue-piece with a latch normally open, movably attached thereto, a plate 25 with an aperture adapted to allow said latch to pass through said plate, and means for
- causing said latch to resume its normal position after passing through said plate.
5. A safety device consisting in the combination of a tongue-piece with a latch normally open, movably attached thereto, a plate with an aperture adapted to allow said latch to pass through said plate, means for causing said latch to resume its normal position after 30 passing through said plate, and stops on said plate to engage said latch.
6. The combination of a tongue-piece with a shank, having a recess, latches normally open, movably attached to said shank, a plate 35 with an aperture adapted to permit the passage of said tongue-piece through said plate, means for causing said latches to close while passing through said plate, other means for causing said latches to open after passing through said plate, and stops on said plate to engage said latches.
- In testimony whereof I have signed my name to this specification in the presence of two subscribing witnesses.

FRED S. PAYNE.
